UNITED STATES PATENT OFFICE.

THOMAS SCANTLIN AND JAMES M. SCANTLIN, OF EVANSVILLE, INDIANA.

EVAPORATOR-FURNACE.

SPECIFICATION forming part of Letters Patent No. 296,072, dated April 1, 1884.

Application filed May 24, 1883. (No model.)

To all whom it may concern:

Be it known that we, THOMAS SCANTLIN and JAMES M. SCANTLIN, both citizens of the United States, residing at Evansville, in the county of Vanderburgh and State of Indiana, have invented certain new and useful Improvements in Evaporator-Furnaces, of which the following is a specification, reference being had therein to the accompanying drawings.

10 This invention relates to those portable evaporators the furnaces of which are mounted on a pair of rockers, in order that either end of the apparatus may be raised or lowered, as occasion may require. Heretofore such rockers have been permanently riveted to the sides of the furnace, thereby producing a very heavy and bulky structure, and rendering the rockers liable to be bent or broken off in transporting the apparatus.

15 Our improvement consists in attaching to the furnace-sides suitable sockets or keepers with which the rockers are engaged, but from which they can be readily detached after unbolting either one of the end sockets on each 20 side of the furnace, as hereinafter more fully described.

25 In the annexed drawings, Figures 1 and 2 are elevations showing the two opposite sides of an evaporator-furnace mounted on our improved rockers. Fig. 3 is a transverse section of said furnace, taken in the plane of the vertical braces F G. Fig. 4 is an elevation of one of said rockers detached from the furnace.

The furnace A may be of any desired size, 30 shape, and material; but we prefer to construct it in accordance with the drawings and specifications of the patent granted to us July 25, 1865, No. 48,982. Attached to one side of this furnace, and near the top of the same, are 35 three sockets or keepers, B B' B'', supplemented by as many similar devices, C C' C'', on the opposite side of said furnace. Of these sets of sockets, the ones B B'' receive the opposite ends of a rocker, D, while the sockets C C'' admit the ends of the other rocker, E. The intermediate sockets, B' C', receive the upper 40 ends of vertical braces F G, the lower ends of the latter being securely riveted, respectively, to the rockers D and E.

45 H H' are inclined stays uniting the brace F to the rocker D. I I' are similar stays connecting the opposite vertical brace, G, with

rocker E. Furthermore, these central or vertical braces, F G, are stiffened with a pair of transverse braces, J J', crossing each other under the furnace, as seen in Fig. 3. These transverse bars J J' are connected to the vertical braces F G, either with bolts or screws j, so as to be readily detached therefrom; but the other bars, H H' and I I', are permanently riveted to 55 said braces F G, and also to the respective rockers. The vertical braces F G and rockers D E are preferably made of angle-iron, so as to combine strength with lightness. As the rocker D, vertical brace F, and inclined stays 60 H H' (seen in Fig. 4) constitute a structure that is complete in itself, it is evident said device 65 can be readily applied to the furnace A by simply inserting the upper end of said brace F in the socket B' and slipping one end of the 70 rocker D into the socket B''. The other socket, B, is then applied to the opposite end of rocker D, and being now bolted to the furnace said rocker is immovably clamped in its proper place; but, if desired, the sockets B B' may be 75 fixtures, and the one B'' be detached preparatory to the application of the rocker D. It is also apparent that the other rocker, E G I I', can be as readily secured to the opposite side of furnace A by disengaging one of the end 80 sockets C or C'', then applying said rocker and brace to the fixed sockets, and finally fastening the detached socket to the exposed extremity of rocker E.

The cross-bars J J' being now bolted to the 85 vertical braces F G, the furnace is at once ready for the application of the evaporating-pan, which latter may be of any approved construction.

From the above description, it is evident the 90 rockers are not retained in place with rivets or other permanent devices, but are simply coupled to the furnace by means of the sockets, keepers, or clip-plates, or bolted directly to the sides of said furnace. Consequently said rockers 95 can be readily detached from the furnace after removing either of the end sockets B or B'' or C or C''. By referring to Figs. 3 and 4, it will be noticed that the length of the center brace F is somewhat less than the width of furnace 100 A, and as the rocker D is shorter than the latter, it is apparent that said rocker and its companion E G can be stowed therein for transportation. Furthermore, the capacity of this

concave furnace is such as to admit the smoke-pipe and bars J J' in addition to the rockers, thereby rendering the apparatus self-contained and diminishing the chances of any of the 5 parts being either broken or lost while being shipped from place to place.

In the drawings the various keepers are represented as screwed or bolted to the sides of the furnace; but the method of attaching said 10 devices and the shape of the same may be varied to suit any special construction of apparatus.

We claim as our invention—

1. The combination, with an evaporator-furnace, of a pair of rockers readily detachable 15 from each other, and also from the furnace, for the purpose of being stowed within the latter, as herein described.

2. The combination, with an evaporator-furnace, of a pair of rockers readily detachable 20

from each other, and also from sockets fastened to the sides of the furnace, for the purpose of permitting said rockers to be stowed within said furnace, as herein described.

3. The combination of furnace A, sockets B 25 B' B" C C' C", rockers D E, and vertical braces F G, said rockers and braces being inserted in said sockets, substantially as herein described.

4. The combination of furnace A, sockets B B' B" C C' C", rockers D E, vertical braces F 30 G, inclined stays H H' I I', and crossed rods J J', which latter are attached to said braces F G, substantially as herein described.

In testimony whereof we affix our signatures in presence of two witnesses.

THOMAS SCANTLIN.

JAMES M. SCANTLIN.
